ALFRED HUTCHINSON, OF PHILADELPHIA, PENNSYLVANIA, ASSIGNOR TO HIMSELF AND STEPHEN H. MARKLEY, OF SAME PLACE.

Letters Patent No. 84,947, dated December 15, 1868.

IMPROVED SCHOOL-DESK AND SEAT.

The Schedule referred to in these Letters Patent and making part of the same.

To all whom it may concern:

Be it known that I, ALFRED HUTCHINSON, of the city and county of Philadelphia, and State of Pennsylvania, have invented a new and useful Improvement in Seats for School-Desks, &c.; and I do hereby declare that the following is a full, clear, and exact description of the same, reference being had to the accompanying sheet of drawings, and to the letters of reference marked thereon.

My invention consists in the adaptation of a folding-seat chair to the back of a school-desk, a separate, distinct chair being provided for each pupil, so that one pupil is not incommoded by the movements of another.

The construction and arrangement promote both the health and comfort of the pupil. The back, being inclined and curved, is adjusted to the shape of the spinal column, and gives it support just where it is most needed.

On reference to the accompanying sheet of drawings making part of this specification—

Figure 1 is a perspective view, and

Figure 2, a perspective view, showing the position of the back-stop *c* on the elbow *a*.

Similar letters refer to similar parts in the two views.

A is a school-desk, of the usual pattern, to the back of which are fixed the chairs *B B'*, which are in all respects similar to the chairs common in use, dispensing with the use of legs.

The chairs are supported by their elbows, *a a*, being secured to the back of the desk.

The seats, *C C'* are closing. When not in use they can be rotated on the pivots *b b*, by which they are hinged to the elbows *a a*, and take the vertical position shown at *C*.

It will be readily seen that each chair forms a separate, independent seat, which enables the pupil to

stand in his place, when reciting, without interfering with the pupil occupying the same desk.

The portions of the seat on each side of the pivots *b b* are, as nearly as possible to their proper working, in equilibrium, to prevent any noise or inconvenience from the seat suddenly turning from a vertical position and striking violently against the lugs *c c* on the ends of the elbows. These lugs serve as back-stops, and support the seat in its horizontal position when in use. They can also be tipped with rubber, which will cushion the blow or force of the falling seat.

The rim of each seat can be of iron or other suitable material, with a recessed centre, and the seat be fitted to set into the recess, by which means the seat can be of wood, cane, or upholstered. The back can also be upholstered or caned.

The chair is so constructed as to promote both the health and the bodily comfort of the scholar. The back being similar to that of an ordinary chair, inclined and curved, is suited to the curvature of the back, and supports it with comfort. The combined desk and independent closing chair enables each pupil to recite the exercises standing, without incommoding his fellow or moving into the aisle between the desks.

What I claim as my invention, and desire to secure by Letters Patent, is—

The combination, with a double desk, *A*, of separate seats, *C C'*, each folding up to the front of the desk independently of the other, substantially as and for the purpose herein specified.

In testimony whereof, I hereunto sign my name to this specification, in presence of two subscribing witnesses

Witnesses: ALFRED HUTCHINSON.
